UNITED STATES PATENT OFFICE.

ERNST SIMON, OF VIENNA, AUSTRIA-HUNGARY.

METHOD OF PRODUCING FROM AMBER, AMBROID, OR THE LIKE, IN MASS, CIGARETTE-HOLDERS, PIPE-STEMS, &c.

SPECIFICATION forming part of Letters Patent No. 742,245, dated October 27, 1903.

Application filed May 2, 1903. Serial No. 155,310. (No model.)

To all whom it may concern:

Be it known that I, ERNST SIMON, a subject of the Emperor of Austria-Hungary, residing at Vienna, Austria-Hungary, have invented 5 certain new and useful Improvements in the Method of Producing from Amber or Ambroid Mouthpieces for Cigars and Cigarettes, Pipe-STEMS, &c., of which the following is a specification.

10 My invention has relation to the production from amber or ambroid by heat and compression a blank adapted to form a mouthpiece or holder for a cigar or cigarette and a stem for a pipe, as well as other articles for some- 15 what analogous purposes, of substantial density and which in finishing will be given a high luster or brilliancy.

Hitherto it has been the general practice to form amber into blocks or the like and to cut 20 these blocks up into sections of near the size required to form blanks to become when finished mouthpieces or the like; but such a method of production was not only expensive, but laborious, as well as occasioning undue 25 waste of material in the finishing of the article. This method also involved several different operations to transform the sections into blanks of the shape or form required and then into mouthpieces.

30 The principal object of my present invention is to obviate the foregoing disadvantageous features mentioned, among others, and to produce from amber or ambroid under heat and pressure a blank of required shape or 35 form and a blank exceedingly hard or unnaturally dense, which in finishing can be given a high luster or brilliancy and with all the characteristic properties of clear or highly-clouded amber, but with far greater strength, 40 and produced much less expensively as compared with the clear or highly-clouded amber goods of high quality now on the market.

The nature, characteristic features, and scope of my present invention will be more 45 fully understood from the following description, taken in connection with the accompanying drawings, illustrating a hydraulically-operated mold-press and reservoir in one form for carrying out practically therein the 50 method of my said invention, in which—

Figure 1 is a vertical sectional view of a

suitable reservoir for containing the melted amber or ambroid, showing a series of rods or standards for the reception of the press-plate of the actuating means for forcing the 55 mass into the mold-blocks of the press. Fig. 2 is a similar view of the reservoir for containing the molten amber or ambroid with the superposed mold blocks of the press having open-ended conical-shaped individual 6c hollows or chambers arranged in series therein, this view showing a hydraulically-actuated mold-press in a practical form for carrying out therein the method of my said invention, the mold-press being shown in a position 65 adapted when pressure is exerted to force the mass contained in the reservoir into the respective individual unconnected hollows or chambers of each block registering in superposed relationship with each other. Fig. 3 is 70 a similar view of the mold-press, showing the same in an operated position with the molten mass forced into and filling the hollows or chambers of the superposed blocks of the press. Fig. 4 is an elevational view of the 75 type or form of blank molded under hydraulic pressure in one of the hollows or chambers of the blocks of the press of Figs. 2 and 3. Fig. 5 is a lower end view of the blank of Fig. 4, showing the configuration or shape thereof. 80 Fig. 6 is an elevational view of what is termed a "blank" for a saddle-mouthpiece for a pipe adapted to be formed in a hollow or chamber, of modified form to that shown in Figs. 2 and 3, of each block of the mold-press; and Fig. 85 7 is a lower end view of the saddle mouth-piece blank of Fig. 5.

Referring to the drawings, A represents the reservoir for containing a mass of amber or ambroid in a heated condition. 90

a represents a series of partially-threaded rods or standards for the reception of the press-plate a², as illustrated in Figs. 2 and 3, the upper ends of the rods or standards being provided with securing or tightening nuts a³. 95

B is the mold-press, consisting, as shown, of two superposed mold-blocks b and b', each provided, as shown, with a vertical series of individual unconnected open-ended conical-shape hollows or chambers b² and b³, so arranged as to register each with the other in their superposed relationship, and between 100

each block as so arranged is interposed a perforated strip or disk *c* at the point of registry of one hollow or chamber with another in superposed relationship of the mold-blocks 5 *b* and *b'*, so that each block can be readily removed from the other after the blank of amber or ambroid has cooled off or become cold in each hollow or chamber of the respective blocks of the press B. The individual 10 unconnected hollows or chambers *b*² and *b*³ of each block, open at both ends, are of a length corresponding with the height of the block. Beneath and upon which rests the lower block of the press is suitably arranged a series 15 of sprues or gates *d* from the reservoir A, as clearly illustrated in Figs. 2 and 3. By arranging the mold-press with but one set of sprues or gates *d* for the series of superposed mold-blocks of the press B waste of the amber or ambroid is reduced to a minimum, since the one series of gates or sprues *d* serves to supply the series of superposed registering 20 hollows or chambers of the blocks of the press B. The interposed perforated disks, partitions, or strips *c* between the superposed blocks *b* and *b'*, as illustrated in Figs. 2 and 3, reduce waste of material at the points of registry of the hollows or chambers with each other; but more particularly such arrangement 25 enables ready separation of blocks without affecting the formed blanks in the hollows or chambers thereof.

e in Figs. 2 and 3 is an interposed cap-plate adapted to close the upper open ends of the 30 block *b* of the mold-press and is made so as to fit snugly into the recess *a*⁴ of the press-plate *a*² of the hydraulic ram *a*⁵. After the hydraulic ram *a*⁵ has forced the press-plate *a*² into the position shown in Fig. 3 and 35 the mass has completely filled out the series of hollows or chambers *b*² and *b*³ of the respective superposed mold-blocks *b* and *b'* of the press B the nuts *a*³ are screwed to the plate *a*² on the threaded portion of the series 40 of rods or standards *a*. Then the ram is elevated and the mold-pieces removed from the hydraulic means thereof, and when the molded mass in the hollows or chambers of said blocks has cooled off or become cold the nuts 45 *a*³ are loosened and the respective mold-blocks *b* and *b'* separated or parted and the blanks then removed from the hollows or chambers *b*² and *b*³ of the blocks *b* and *b'* of the press B by any suitable small punch- 50 tool. (Not shown.) The blank *f* thus formed 55 will have the form illustrated in Figs. 4 and 5 if the hollows or chambers *b*² and *b*³ of the blocks *b* and *b'* are of the type illustrated in Figs. 2 and 3 with flat bases and will correspond 60 in length with the height of each hollow or chamber.

Blanks of the saddle type *g*, as illustrated in Figs. 6 and 7, can be readily formed in such a mold-press B as described, provided 65 the blocks have hollows or chambers of the outline or contour of such type of blanks to become what is well known as "saddle"

mouthpieces for pipes and cigarette and cigar holders. It is also obvious that amber or ambroid may be formed according to my invention into various other types of blocks, which will depend in each instance upon the shape or form of the hollows or chambers of the press B.

The process of my invention as exemplified 70 in one form of a hydraulic mold-press hereinbefore described may be briefly explained as follows: The fragments, pieces, or other forms of amber or ambroid are placed in the reservoir A and subjected to heat of required 75 temperature to bring the fragments, particles, or pieces in mass to the consistency of a 80 pasty or plastic condition, and in such heated condition the mass is forced into the hollows or chambers of the blocks of the mold- 85 press B to completely fill the hollows or chambers thereof under hydraulic pressure, the heating and pressing of the mass being practically continuous until the blanks have been 90 completely formed in the hollows or chambers of the press of substantial or unnatural density, so that in the finishing of the blank produced for use a high luster or brilliancy 95 can be given thereto with the least possible labor, giving an article of a clear or highly- 100 clouded character, as required, inexpensively as compared with the methods now practiced for producing such goods, the finishing being accomplished by the formation of the undercut or projection at one end, boring of 105 the interior, and polishing or burnishing of the surface by suitable well-known appliances if the articles are intended for pipe- 110 stems, cigar and cigarette holders, or the like. The making of such articles in substantially the manner explained will be 115 exceedingly strong and dense, and thus receive a far higher degree of polish or be of greater brilliancy in finish than any like types of articles now being made from blocks of amber 120 by the slow or tedious methods now practiced for producing such articles.

I am aware that it is not new to mold amber under the application of heat and pressure in sectional or two-part molds into mouthpieces or the like; but amber articles so molded have fins and other forms of waste attached thereto when liberated from the molds that must be removed before being finished, which occasions unnecessary expense and labor that 125 it is very desirable to avoid. Moreover, in sectional molds the amber cannot be given by the molding therein, as practice has proven, the requisite degree of density to insure a high luster or brilliancy being given to the 130 finished article without increasing the size of the fins and other objectionable forms of waste from the pressure exerted when produced according to the processes and apparatus described in the United States Letters Patents 135 No. 234,756, of November 23, 1880; No. 237,497, of February 8, 1881, and No. 461,722, of October 20, 1891, and therefore I disclaim as of my invention any features set out in the said

recited Letters Patents; but what I do claim as new at the date hereof is the production of blanks for mouthpieces or other uses from amber or ambroid of uniform unnatural density without fins or other objectionable waste attached to the blanks in their formation, so as to permit in the finishing of a high degree of luster or brilliancy being given to the finished article. The method of producing such articles according to my invention is a decided advance in the art when the nature and characteristic properties of amber or ambroid are considered and as understood by those practically skilled in the art of producing such articles.

Having thus described the nature and object of my invention, what I claim as new, and desire to secure by Letters Patent, is—

1. The method of molding blanks to become mouthpieces for pipes, cigars, &c., from amber or ambroid, which consists in molding the amber or ambroid under a pressure sufficient to render the same unnaturally dense, substantially as and for the purposes described.

2. The method of molding blanks to become mouthpieces for pipes, cigars, &c., from amber or ambroid, which consists in molding the amber or ambroid in a heated condition un-

der a pressure sufficient to render the same unnaturally dense and allowing the molded amber or ambroid to cool or become cold in its dense blank form, the density of the blank permitting in the finishing operation, without chipping or sealing, a high luster or brilliancy being given thereto, substantially as described.

3. The method of molding blanks to become mouthpieces for pipes, cigars, &c., from amber or ambroid, which consists in molding the material directly into a form which after finishing becomes the article required, and in subjecting said material during the molding operation to a pressure sufficient to increase the density of the blank beyond the natural density of the amber or ambroid material from which the blank is produced, whereby a blank of required shape and uniform density is obtained, as and for the purposes described.

In testimony whereof I have hereunto set my signature in the presence of two subscribing witnesses.

ERNST SIMON.
